DESIGN FOR AN ELECTRICAL PLUG CAP

William Huppert, New York, N. Y.

Application October 30, 1946, Serial No. 134,390

Term of patent 14 years

(Cl. D26—1)

To all whom it may concern:

Be it known that I, William Huppert, a citizen of the United States and a resident of the city, county, and State of New York, have invented a new, original, and ornamental Design for an Electrical Plug Cap, of which the following is a specification, reference being had to the accompanying drawings, forming part thereof, in which:

Figure 1 is a side view of an electrical plug cap, showing my new design;

Fig. 2 is an end view thereof;

Fig. 3 is a top plan view; and

Fig. 4 is a bottom plan view.

The characteristic features of my design reside in the portions shown in full lines.

I claim:

The ornamental design for an electrical plug cap, substantially as shown and described.

WILLIAM HUPPERT.
